WOMAN'S SCARF OR THE LIKE

Stanley Herzman, Scarsdale, N. Y.

Application August 20, 1954, Serial No. 31,948

Term of patent 3½ years

(Cl. D3—12)

To all whom it may concern:

Be it known I, Stanley Herzman, a citizen of the United States, residing at 24 Shawnee Road, Scarsdale, county of Westchester, and State of New York, have invented a new, original, and ornamental Design for a Woman's Scarf or the like, of which the following is a specification, reference being had to the accompanying drawing, forming a part hereof, in which the figure is a plan view of a woman's scarf showing my new design.

I claim:

The ornamental design for a woman's scarf or the like, as shown.
